CLAIM

The ornamental design for a temperature control unit for showers and baths, as shown and described.

DESCRIPTION

FIG. 1 is a front elevational view of a temperature control unit for showers and baths showing a use of my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing is for illustrative purposes only and forms no part of the claimed design.

FIG. 1

FIG. 2

*FIG. 3**FIG. 4**FIG. 5**FIG. 6*
